UNITED STATES PATENT OFFICE.

WILLIAM G. PRICE, OF YAKIMA, WASHINGTON.

BOX-MAKING BENCH.

1,378,899.

Specification of Letters Patent. Patented May 24, 1921.

Application filed April 12, 1920. Serial No. 373,239.

To all whom it may concern:

Be it known that I, WILLIAM G. PRICE, a citizen of the United States, and resident of Yakima, in the county of Yakima and State 5 of Washington, have invented a new and useful Improvement in Box-Making Benches; and I do hereby declare the following to be a full, clear, and exact description thereof.

My invention relates to a box making 10 bench, adapted to support the ends, sides, bottom and cleats of a box in the proper position with relation to each other, preparatory to the nailing of these parts together.

The object of my invention is to provide 15 simple and efficient means for so supporting the parts of a box that it can be easily rotated or turned from the first to the second and third positions required for nailing the parts together, and in addition to provide means 20 for supporting the cleats in position for nailing, without covering that part of the ends of the box where the hammer must be used to drive back the points of badly driven projecting nails, and furthermore to provide 25 means for quickly adjusting the supporting device in height and length to adapt it to the making of boxes of various heights and lengths.

To these ends my invention comprises the 30 novel features hereinafter set forth and claimed.

Referring to the accompanying drawings, Figure 1 is a front view of my improved box making bench, Fig. 2 is a plan view; 35 Fig. 3 is an end view showing a box in position for nailing on the bottom and cleats, and Fig. 4 is a view showing the partial box in position for nailing on the bottom and cleats.

40 In the accompanying drawings, 1 designates the bench frame which is usually made of wood, properly braced to give the requisite stability and strength. Secured to the rear uprights 1^a of the bench is the form 2 which is preferably made of metal.

The bench has the steel or other metal plates 3 and 4 secured thereto, which form a flat even surface for the box-ends in its course of construction.

50 The bench 1 has the horizontally projecting arms 5, 6, 7, 8, 9, 10, 11 and 12, and the brackets 13 and 14 secured to the arms 9, 10, 11 and 12, said brackets forming the rack for supporting the blanks from which the 55 box is to be made.

The form 2 is attached to the bench by means of the bolts 15 and 16, which pass through the slots 17 and 18, thereby providing for the vertical adjustment of the form with reference to the bench. The form 2 is 60 preferably composed of the angular plates 19 and 20 secured together by means of the bolts 22 and 15 to form a V-shaped structure. The bolt 22 passes through a slot 23 formed in the plate 19, and the slot 24 formed in the 65 plate 20 through which the bolt 15 passes, permits plates 19 and 20 to slide over each other to provide for the adjustment of said plates according to the size of box to be made. 70

The plate 20 of the form 2 has secured thereto the vertically extending bars 25, 26, 27, 28 and 29 and the bracket 30. The bracket 30 has the spring-hinge 31 which supports the swinging plate 32. The swinging plate 32 has the bent corner 33. The outwardly extending wing 20^a of the plate 20 has the bent corner 57 also. 75

The vertically extending bars 28 and 29 are secured to the plate 20 by means of bolts 80 34 and 35. In order to provide for the adjustment of the bars 28 and 29 at different heights, I provide extra holes 36, 37, 38 and 39 in the bars 28 and 29.

The spacing washer 40 is interposed between the plate 19 and the bench. 85

Secured to the plate 19 is the bar 41 and the bracket 42. The outwardly projecting wing 19^a of the plate 19 has the bent corner 43. 90

The bracket 42 supports the spring-hinge 44 which carries the swinging plate 45. The swinging plate 45 carries the hinge 46 which connects the swinging plate 45 with the oscillating plate 48. The oscillating plate 48 95 has the bent corner 49, and projecting up from said plate are the bars 50 and 51.

The operation of putting a box together where my improved bench is employed is 100 as follows:

One box-end 52 is placed between the wing 19^a of the plate 19 and the oscillating plate 48, the spring in the hinge 44 causing the said oscillating plate to clamp the box-end 52 against the stationary wing 19^a. In like 105 manner the other box-end is placed between the wing 20^a and the swinging plate 32, the spring 31 causing the clamp to rotate against the stationary wing 20^a. The bent or curved corners 33, 57, 43 and 49 facilitate the plac- 110

ing of the box-ends in the above described position as they present flaring openings to aid in guiding the box-ends into position.

The space between the swinging plates 32 and 48 and the wings 19^a and 20^a is less than the thickness of a box-end so that some movement of the swinging plates 32 and 48 is required for the insertion of the box-ends.

10 The side 53 of the box is first placed on top of the box-ends after they have been inserted in the manner described and resting against the vertical projecting bars 28 and 29. With the side 53 in this position said 15 side is then nailed to the box-ends. The partially formed box is then rotated or turned by hand toward the operator one quarter turn to the position shown in Figs. 3 and 4.

20 The box-bottom 54 is then placed on the ends bearing against the projecting bars 28 and 29, whereupon the box cleats 55 and 56 are placed on said box-bottom bearing against the bars 25, 26, 27, 41, 50 and 51, 25 whereupon the cleats and bottom are together nailed to the box-ends. The partially formed box is again rotated or turned one quarter toward the operator and the other side is nailed on when the box is finished and is withdrawn from the form.

In the box making benches heretofore generally employed it has been customary to have two inner clamping plates corresponding to plate 32 on the inside of the outer 35 stationary plates corresponding to 19^a and 20^a. With this construction of form the box when partially completed rested rigidly between the rigid wings and if the box-ends were warped a trifle, and they are almost 40 always warped, the warped surface would catch under the stationary wings and resist the rotation of the box and the pulling of the box out of the form after it was completed. By my invention this difficulty is 45 overcome by having one spring clamping plate 32 inside of the wing 20^a and the other spring clamping plate 48 outside of the wing 19^a. This construction permits a 50 box with warped ends to be rotated in the form and removed with perfect ease.

The projecting bars 25, 26, 27, 41, 50 and

51 hold the cleats in their proper positions for nailing and leave a large portion of the ends of the box exposed, so that a nail which is driven at an angle from vertical and projects outside or through the box-end can be driven back up and removed with the claw of the driving hatchet without moving the box.

By clamping the parts together, using 6^a slotted holes for the bolts, I make the form adjustable in length for different sizes of boxes, and by clamping the form to the bench by slot holes in the bench, I make the form adjustable for various heights of 65 boxes.

The construction shown greatly increases the speed of manufacture, and when boxes have warped material, it produces a more accurately shaped box.

70 The adjustable features of the combined form and bench enable it to be used to make many sizes of fruit-boxes.

What I claim is:

1. In a box making bench, the combination with a suitable frame of two oppositely disposed rigid box-end supports, a yielding clamping member arranged on the inside of one of said box-end supports, a yielding clamping member on the outside of the 75 other rigid box-end support, said last-named clamping member comprising a swinging plate, and an oscillating plate hinged thereto.

2. In a box making bench, the combination with a suitable frame of two oppositely disposed box-end supports, the upper outer corners of said supports being bent, and yielding clamping members, one of said yielding clamping members arranged on the 80 inside of one of said box-end supports and the other arranged on the outside of said other box-end support, said clamping members having bent corners forming with the bent corners of said supports flaring openings to receive the end of the box.

85 In testimony whereof, I, the said WILLIAM G. PRICE, have hereunto set my hand.

WILLIAM G. PRICE.

Witnesses:
